UNITED STATES PATENT OFFICE

GEORGE V. HODGKINS, OF MINNEAPOLIS, MINNESOTA, ASSIGNOR TO THE VALENTINE CLARK CO., OF ST. PAUL, MINNESOTA, A CORPORATION OF ILLINOIS

POLE-PUNCHING MACHINE

Application filed June 21, 1930. Serial No. 462,905.

This invention relates to improvements in apparatus for perforating wood preparatory to receiving preservative material. The invention is an improvement over the inventions of Patent Number 1,701,324.

Main objects of this invention are to so manipulate or operate the perforating instrumentalities as to obtain uniformity of depth of perforation, and in a manner not to break or bruise the sapwood, and to perform these operations automatically.

In preparing poles for impregnation, it has been difficult (because of the circumferentially ununiform configurations of the poles) to obtain a uniform depth of punching and at the same time prevent injury to the sapwood. In other words, it has, before this invention, been practically impossible to prevent over-stroke or under-stroke, or over or under-run of the punching instrumentalities. The over-stroke not only has resulted in the breaking of the sapwood, but sometimes in the breaking of the mechanism itself.

Important objects are, therefore, to provide mechanism for obtaining uniform and proper depth of perforation; for preventing over-stroke and injury to the mechanism; for preventing over-stroke and injury to the sapwood; to provide means which automatically compensates for circumferential inequalities in the log being punched, by moving either the work, or the punching instrumentalities toward or away from one another, conformably to the degree and direction of the variation; to provide hydraulically-operable means for accomplishing the above results; to provide means hydraulically-operable for raising the pole to and lowering it from operative position; to provide means for synchronizing and co-ordinating the devices for performing their various functions; and generally to provide a comparatively simple practicable and efficient device for the purposes in hand.

Features of the invention include the broad idea of automatically controlling punching instrumentalities in a device of this kind, to obtain uniform depth of punching and prevent injury to the sapwood; the details of

construction for carrying out the scheme; and combinations of elements whereby the control is synchronized with the means for reciprocating the punching head and obtaining step-by-step rotation of the work, along with various details of construction shown.

Advantages, features and objects of the invention will appear in the description of the drawings forming part of this application, and in said drawings

Figure 1 is a top plan view;

Figure 2 is a vertical sectional elevation taken substantially on line 2—2 of Figure 1;

Figure 3 is a side elevation partly in section viewed from that side of Figure 1 indicated by line 3—3;

Figure 4 is a schematic view illustrating the automatic, as well as the manual controls;

Figure 5 is a vertical section illustrating part of the valved structures of the fluid-operable control system;

Figure 6 is a vertical section of one of the valves taken on line 6—6 of Figure 5;

Figure 7 is a vertical sectional view of the other valve taken on line 7—7 of Figure 5;

Figure 8 is a detail view of the timing and stroke-adjusting means for the work-engaging and valve-operating levers;

Figure 9 is a plan section of the structure of Figure 8 taken on line 9—9 of that figure; and

Figure 10 is a vertical cross-section illustrating the construction of one form of punching instrumentality which may be automatically controlled by the device herein, or in relation to which the work may be automatically adjusted.

The structural-iron supporting frame for the mechanism is generally indicated 1, and comprises, among other elements, a bridging structure generally indicated at 2, see Figure 2, supported at opposite sides on I-beams 3 in turn supported on suitable foundations. Inasmuch as the perforating apparatus and

its structure and operation are described in detail in Patent Number 1,701,324, a complete detailed description is not entered into herein. Vertically slidably guided in the frame work just described is an element 5 (as a cross

head) which has vertically slidable thereon a structure 5^a, see Figure 10, having a steam chamber 5^b. The bottom of this chamber is formed by a plate 6, and carried by this plate are a series of adjacently disposed vertical tubes 7 arranged in parallel relation and secured against axial movement and extending downwardly toward the work support 25. Reciprocable within each cylinder is a piston 8 having a head 9 and punching pins 10 in the head. The outward movement of the piston is limited by a plate 11 attached to the extension of the piston, this plate engaging the upper end of the cylinder 7. Constant pressure is maintained in the chamber 5^b by the introduction of proper pressure fluid through the pipe 15.

The chambered structure 5^a is supported by pairs of toggle links 16. The extremities of the members of each pair are pivoted respectively to cross-head 5 and chambered structure 5^a. The pivot 17 which connects the pair of toggle members also connects them to a piston rod 18. There are two pairs of links attached to each end of the rod, and the piston cylinder 19 lies between them. A suitable valve mechanism controls entry of fluid through the pipes in a manner to reciprocate the piston (not shown) alternately in opposite directions, whereby the links are operated in a manner to alternately lower and raise the chambered structure 5^a and cause its perforating elements 10 to enter and be withdrawn from the work. Of course, the cylinder 19 is carried by the adjustable cross-head 5. Heretofore, the cross-head 5, toggles and chambered element 5^a were moved by a hand-controlled fluid-operable device to adjust the punching instrumentalities relative to the work so as not to over-run and injure the sapwood. It was found to be practically impossible to properly manually accomplish this result.

The work supports (see Figure 4) are respectively indicated at 25-26, the support 25 lying directly under the punching elements 9, see Figure 2, about centrally of the same. The support 26 is, in practice, spaced a considerable distance from the support 25 and acts to raise and lower the outer end of the pole or object being operated upon. The support 25 is raised and lowered by means of hydraulic devices, including a piston and its cylinder 28, while the device 26 is directly supported by a similar piston which operates in a cylinder 29. Each support is provided with two rollers 30 upon which the work 31 rests. The work has been indicated as circumferentially irregular, and the irregularities have been somewhat exaggerated for purposes of illustration.

Means is provided for rotating the work upon the rollers, and includes a mechanism which is synchronized with the punching instrumentalities to rotate the work slightly,

between punching operations, so as to obtain step-by-step presentation of a new surface to be punched. This means includes a pair of sprocket chains 35, see Figures 1 and 3, one arranged at each opposite side of the frame structure previously described. The sprocket chains pass over suitable sprocket gears keyed to shafts 36-37. The shaft 36 is supported in a swinging frame 39 pivoted as at 40. At the bottom of this frame is attached a chain tensioning device including a flexible element 41 passing over roller 42 and having a weight 43. This device, acting upon the swinging frame 39, moves it in a direction to automatically maintain the lower face of the lower runs 45 of the chains 35 in proper frictional contact with the work. The chains are guided at points intermediate the sprocket wheels by guide rollers 46, which engage the top of the bottom run of the chain and that part of the chain lying between these rollers, with one guide roller at each side of the work. This arrangement is best shown in Figure 3. It will be noted that rollers 46 are supported on threaded stems 47, see Figure 3, and these stems are held in suitable bearings, and are connected by beveled gearing 48 with a shaft 49 which has a wrench portion for turning it. By rotating the shaft 49 the guide rolls 46 can be raised or lowered.

The main shaft, see Figures 1 and 3, is indicated 50, and is operated by pulley 51 connected by a suitable belt with a suitable source of power, not shown. A clutch 55 of any preferred construction is adapted, when properly operated, to connect or disconnect the pulley. Upon shaft 50 is mounted an eccentric 57, operating through the connection indicated at 58 to oscillate the pawl arm 59 and pawl 60. This pawl engages the teeth of ratchet wheel 61 keyed to shaft 37. It is evident that the ratchet mechanism will give a step-by-step operation of the shaft 37, and, therefore, the chain, to rotate the work. The work is, of course, rotated after the punching instrumentalities have been withdrawn, or between each punching operation, and the mechanisms are suitably synchronized for this purpose in the following manner: Referring to Figures 1 and 2: The shaft 50 is connected with a shaft 70 by suitable beveled gearing 71. On shaft 70 is a crank disk 72 connected by crank arm 73 with a rod 74 slidable supported in the structure 5^a, and having stops 75 thereon which alternately engage a valve-operating arm 76 attached to the valve rod 77. By this means, the valve is moved to control the piston of the cylinder 19 to operate the toggles so that the log is rolled when the structure 5^a has been raised sufficient to withdraw the punching elements from the work. This piston and valve structure is analogous to the steam chest of a locomotive.

Although most of the devices previously

described are features of the invention, the main feature comprises automatically operable means for adjusting the work with reference to the punching elements so that these elements will at no time be operated in a manner to injure the sapwood.

This automatic device is best shown schematically in Figure 4.

The device for automatically maintaining a predetermined relation between the work and the punches, in this instance, moves the work supports, but could be applied to obtain compensatory movements of the punch frame. The device, see Figure 4, includes a fluid system having a supply tank 80, a pressure tank 81, and a pump 82 diagrammatically indicated, which pump draws fluid from the supply tank and compresses it in the pressure tank. A hand valve 83 controls flow from the pressure tank 81 in one direction, and another hand valve indicated at 85 controls fluid flow in the opposite direction and also controls the return line to the supply tank (see below). Another hand valve 86 controls the flow to and from the cylinder 29. Supply pipe 87 connects tank 81 with valve 83, and valve 83 is connected by pipe 88 with the throttle valve 89. The valve 89 is connected by pipe 99 with valve chamber 92 of the valve casing generally indicated at 91. Pressure tank is also connected by pipe 93 with the port 94 of valve 85 and this valve 85 is also connected by port 95 with port 96 of valve 86. Port 97 connects valve 86 through pipe 98 with the cylinder 29. Port 100 of valve 85 is connected through pipe 101 with the supply tank 80. The ports 95-96 are connected by pipe 102 and a branch pipe 103 leads from this connection to valve 90, and valve 90 is connected by branch 104 with pipe 110 adjacent cylinder 28. It is evident that by properly positioning the piston-like valves 85-86, the pressure line can be opened to cylinder 29 through ports 94, 95, 96 and 97. When this line is open and when the valve 85 is properly manipulated the cylinder 29 can be put in communication with the supply tank to empty thereinto. In this case, the fluid passes through ports 97, 96, 95, 100 and thence to the supply tank. Chamber 92 of valve structure 91 is connected through port 105 with chamber 106 in turn connected by pipe 107 with check valve 108. The check valve opens only in direction of the arrow A. Check valve 108 is connected by pipe 109 with pipe 110 which pipe is in turn connected with the cylinder 28. Valve structure 112 provides a chamber 113 connected by valve control port 114 with chamber 115. Chamber 115 is connected by pipe 116 with pipe 101 leading to the supply tank 80. Chamber 113 is connected by supply pipe 117, with supply pipes 109-110. Valve stems 120-121 respectively control valves which control ports

105-114. The stems 120 and 121 are engaged by the lower surface of the lever 130 and by portions of such surface which lie at opposite sides of the pivot 131. Suitable springs cause the valves to close automatically. The valves are opened against the tension of these springs, depending on the direction of oscillation of lever 130 about the pivot 131. When one of these valves is closed, the other is open, and vice versa. When port 105 is opened and port 114 is closed, the work support 25 is raised. When port 114 is opened and 105 is closed, the work support is lowered.

The means for accomplishing this alternate opening and closing of the valves includes a lever 130 pivoted as at 131 and having a counterweight 132 on one arm and having the other arm connected by an adjustable link mechanism, generally designated 133, with arm 134 attached to shaft 135, see Figure 1. Also attached to the shaft are two arms 136, diametrically related to the first arm but at the opposite side of the shaft, and each arm 136 has a roller 138 pivoted thereon which engages the work 31. An arm 136 lies at each opposite end and laterally of the punching instrumentalities, see Figures 1 and 2. As the contour of the log changes, the lever 136 is rocked in conformity to the variation in the circumferential configuration of the work, and through arm 134, link 133, and lever 130 the valve stems are correspondingly moved. In this instance, when the roller is lowered, due to increased distance of the periphery of the work from the punches, fluid is introduced into cylinder 28 to raise the work support and bring the work nearer to the punching instrumentalities. When the roller is raised, or when the distance between its periphery and the punches decreases, fluid is exhausted from the cylinder 28 and the work support moves downwardly, moving the log a little farther away from the punching instrumentalities. The movements in either direction are comparatively slight or, in other words, lie within a comparatively small range. The action is practically instantaneous. The range of movement can be changed, and timed, and adjustments in this regard can be very accurately made by the device best shown in Figures 8 and 9. To this end, the arm 134 is longitudinally slotted as at 150, see Figures 8 and 9, and in this slot is slidably arranged a block 151, pivoted as 152 to and between arms 153 of block 154. This block is in threaded connection with a pin 155, which pin has an extension 156 in threaded engagement as at 157 with adjusting sleeve 158. The threaded portion 156 has a jamb nut 159. The arm 160 of lever 130 has pivoted thereto as at 161, a pin 170 having a reduced extension 171 slidable in sleeve 158, and has its end abutting the end of the threaded extension 156. The weight 132 tends to

maintain this abutting relation. Thus the distance between the pivotal points 152 and 161 may be varied and, therefore, the roller of lever 134 may be raised or lowered with reference to the punching instrumentalities. Moreover, a speed variation can be obtained by adjusting the block in slot 151 radially with respect to shaft 135. To this end, a clevis 175 is arranged in the slot and is secured to pin 152. To this clevis, a threaded rod 181 is swiveled as at 182. The rod 181 is in threaded engagement with the arm 134, and suitable jamb nuts 183—184 are employed to secure the rod after adjustment has been made. The rod is provided with a suitable wrench head 185.

By the above described mechanism, used in conjunction with certain other devices, the punching instrumentalities can be perfectly controlled in a manner to obtain the proper depth of punching but without injury to the sapwood.

Hand-control connections are so arranged that when the lever-operated throttle valve 89 is open, the lever-operated valve 90 in the drain or return line from cylinder 28, is closed, and vice versa. The hand valve 83 is kept closed until the machine is ready to start, and until the cylinder 19 has been operated to get rid of the water of condensation. A rod or equivalent element 200 connects the levers of the lever-operated valves 89—90 for movement in unison, one to close when the other opens and vice versa. The throttle lever is indicated at 201, see also Figure 1 and this lever is connected by a rod 201 with the arm of the valve 89. The throttle lever 201, see Figure 1, is also connected by element 202 with the operating arm 203 of the clutch 55. The parts are so arranged and proportioned that when the throttle is operated to open valve 89, clutch 55 is thrown in to connect pulley 51 for operating shaft 50, thus starting the step-by-step, work-rotating mechanism, and the punching instrumentalities, as soon as the device is conditioned for automatically adjusting the work with reference to the punching instrumentalities.

The adjustment of the valve control levers is made in reference to the position of the punching instrumentalities. Let it be supposed that the punch has a two inch stroke, that is, that the head has a two inch range of motion. The wheel which engages the log is then set in some predetermined relation to the bottom of the teeth. It is evident that if the lowermost portion of this wheel were set three inches below the punch tips, no punching could be accomplished because the valve 90 would be open and the log lowered before the punching instrumentalities would engage the log. If the lowermost portion of the wheel is set one and one-half inches below the bottom of the punches, it is evident that the punches will enter one-half an inch into the

log, and the entry distance of the punches is increased as the distance is decreased. In one of the devices which is operating, and which is constructed in accordance with the teachings of this invention, the toggle motion is two inches, and the length of the punches five-eighths of an inch. When the lowermost portion of the roller is set at a distance one and one-half inches below the bottom of the punches, the heads in which the punches are mounted never impinge the surface of the pole in a manner to injure the sapwood, either to compress it or to bruise it.

Operation

Although Figure 4 represents a condition in which the work support 25 is being raised, we will first assume the log-supporting devices 25—26 to be in lowermost position. The work 31 is then laid upon the rollers 30. At this time, throttle valve 89 is closed, valve 90 is open, port 105 is open, port 114 is closed, and the exhaust line from the cylinder 28 to the supply tank 80 is open through 110, 104, valve 90, 103, 102, port 95, port 100 and 101. The exhaust line from cylinder 29 to the supply tank is also open through 98, port 97, port 96, 102, port 95, 100 and 101. The master valves 85 and 86 are arranged near one another so that the operator has immediate access to both.

Valve 85 is now moved to the position shown in Figure 4 to close the exhaust line from cylinder 28 to the supply tank, and to establish a pressure line connection from the pressure tank 81 to the cylinder through 93, port 94, port 95, 103, valve 90, 104, 110. The valve 86 is also moved to a position below that shown in the figure, to establish a pressure line connection from the pressure tank 81 to the cylinder 29, through 93, ports 94 and 95, 102, 96, and ports 97 and 98. The valves 85, and 86 are simultaneously operated so that both work supports simultaneously rise. Ordinarily support 29 rises at a greater rate. This raising of the supports is continued until the work is in approximately the proper operative relation to the punches. The valve 86 is then set at the position shown to close the exhaust line so that work support 26 is held in upper position, and valve 85 is raised from the position shown to establish an exhaust connection from cylinder 28 to supply tank 80, through valve 90. The throttle lever 201 is now operated to open valve 89 and close 90, and throw clutch 55 in, so that the punch and the work-rolling or feeding mechanisms, begin to operate in synchronized relation. The surface of the log is now engaging the roller 138, and if that portion of the surface of the work which is to be punched is too far from the punches, which condition is assumed in Figure 4, the levers are rocked in direction of the full line arrows, port 105 is open, port 114 is closed, and fluid pressure is delivered

from the tank 81 to cylinder 28 through 87, hand valve 83 (previously opened), 88, valve 89, 99, chamber 92, port 105, chamber 106, 107, check valve 108, 109 and 110, to raise the 5 work support, and so position the work that the punches not only enter, but enter exactly to the desired depth. If now, due to some circumferential inequalities, the work assumes a too closely spaced relation to the punches, the 10 levers are rocked in an opposite direction (see dotted line arrow) and port 114 is opened, and port 105 closed. Opening of the port 114 establishes an exhaust communication between the cylinder 28 and the supply tank as 15 follows: (valve 90 being closed) 110, 116, chamber 113, port 114, chamber 115, 116 and 101, and the support 25 is lowered, and the work retracted.

The adjustment response in this system is 20 substantially instantaneous and when the parts are so related that injury to the sap-wood would result, the distance between the punches and the work is increased, and when the parts are so related that the punches 25 would not enter the work to the proper extent, this distance is decreased. This may be accomplished by automatically adjusting either punches or work support, or both, and in its broader aspects, there is no intention to 30 limit the invention. However, at present the most convenient way is to automatically adjust the work support.

I claim as my invention:

1. A device of the class described comprising movable work-supporting instrumentalities, movable punching instrumentalities adapted to operate upon work carried by the support, and means adapted to automatically adjust at least one instrumentality in 40 relation to the other to increase or decrease the distance between them in conformity to circumferential inequalities of the work and in a manner to obtain a uniform depth of punching without injury to the sapwood.

2. A device of the class described comprising movable work-supporting instrumentalities, movable punching instrumentalities adapted to operate upon work carried by the support, and fluid-operable means adapted to 50 automatically adjust at least one instrumentality in relation to the other to increase or decrease the distance between them in conformity to inequalities of the work, and in a manner to obtain a uniform depth of punching without injury to the sapwood.

3. A device of the class described comprising movable work-supporting instrumentalities, movable punching instrumentalities adapted to operate upon work carried by the support, and fluid-operable means adapted to 60 automatically adjust at least one instrumentality in relation to the other to increase or decrease the distance between them in conformity to circumferential inequalities of the

work, and in a manner to obtain a uniform depth of punching without injury to the sap-wood.

4. A device of the class described comprising movable work-supporting instrumentalities, movable punching instrumentalities adapted to operate upon work carried by the support, and fluid-operable means adapted to automatically adjust at least one instrumentality in relation to the other to increase or decrease the distance between them in conformity to circumferential inequalities of the work and in a manner to obtain a uniform depth of punching without injury to the sap-wood, said means including a pair of valves, 70 levers arranged to control the valves, one of said levers having a portion in contact with the surface of the work in a manner to move the lever conformably to surface irregularities.

5. A device of the class described comprising movable work-supporting instrumentalities, movable punching instrumentalities adapted to operate upon work carried by the support, and fluid-operable means adapted to automatically adjust at least one instrumentality in relation to the other to increase or decrease the distance between them in conformity to circumferential inequalities of the work and in a manner to obtain a uniform 80 depth of punching without injury to the sap-wood, said means including valves, levers arranged to control the valves, one of said levers having a portion in contact with the surface of the work in a manner to move the lever 85 conformably to circumferential irregularities.

6. A device of the class described providing a support upon which the work may be turned, a head adapted to reciprocate toward 105 and away from the work and having punching instrumentalities for engaging the work, and a valve-controlled pressure fluid system adapted to operate said work support including an element which engages the work and is 110 moved in opposite directions thereby conformably to inequalities in the work, and which is adapted when moved in one direction to raise the work towards the instrumentalities and when moved in the opposite direction to reverse direction of motion of the work.

7. A device of the class described comprising a work support, a head arranged to be advanced towards and withdrawn from the work support, said head having punching means adapted to engage the work and hydraulic means for raising and lowering the work support with reference to the punching instrumentalities including valves and a pilot 120 element which engages the work and follows the inequalities therein, said pilot adapted to control said pressure system through said valves for causing the work support to be moved toward said punching means when said 125

device contacts a depression in the work, and for moving the work away from the punching means when said element contacts a projection of the work.

8. A device of the class described including a work support, punching means adapted to be advanced toward and withdrawn from a log arranged on the support, movable pilot elements engaging the log at opposite sides of the punching instrumentalities to be affected by variations in the circumferential configuration of the log, fluid-operable means controlled by said pilot elements, and adapted to adjust the work support relative to the punching means to prevent over-run of the punching means sufficient to hammer the wood and injure the sapwood, and to obtain a uniform depth of punching, and means for giving a step-by-step rotation to the work between punching operations.

20 In witness whereof, I have hereunto set my hand this 17th day of June, 1930.

GEORGE V. HODGKINS.
